UNITED STATES PATENT OFFICE.

EDWARD T. NOONAN AND JOSEPH V. SCHMILL, OF CHICAGO, ILLINOIS.

POLYCYCLE.

SPECIFICATION forming part of Letters Patent No. 498,484, dated May 30, 1893.

Application filed January 21, 1893. Serial No. 459,255. (No model.)

To all whom it may concern:

Be it known that we, EDWARD T. NOONAN and JOSEPH V. SCHMILL, of the city of Chicago and State of Illinois, have invented certain new and useful Improvements in Polycycles, of which the following is a specification.

Our invention relates to that general class of amusement apparatus, known as "merry-go-rounds" and the like, and by it we attain a stability of construction, insuring safety and pleasure in its use, while its operation is at all times within the control of suitable attendants.

We show in the accompanying drawings four views.

Figure 1, is vertical view of a half section of a circular platform involving our invention. Fig. 2, is a lateral view of the polycycles with a section of the groove wherein they run arranged for use. Fig. 3, is a view of the brake device whereby the operation of the apparatus is placed under control of attendants, and Fig. 4, is a view of the device by which the cycles are rigidly attached to each other.

Similar letters refer to similar parts throughout the several views.

In the accompanying drawings the letter A, denotes a circular platform around which the cycles B in any suitable number revolve in a groove C rigidly held together in such form as to easily make the circuit by the bar D made of pipes bent in form as shown, or of iron or other suitable material made to conform to the same shape. This bar is made in sections with threaded ends and attached together by the caps E. The cycles are provided with the usual seat F, handles G, pedals H.

Each cycle is provided with a bent rod I, firmly attached at its upper end to the inner side of the axle, reaching downward and below the side of the groove in which the cycles run, and there at its lower end is attached to a cable J of suitable material. Reaching

from the center of the platform are four arms K made of any suitable material, designed to reach to the bent rod I, provided at its end next the rod with a block L, of wood or other suitable material, and at its other end with a bevel wheel M, reciprocating with another and larger bevel wheel N, attached to an upright shaft O, fitted at its upper end with geared wheels P, and provided with a threaded end, and engaging another geared wheel Q, which itself is attached to the crank R. The arm K, is provided with a spring S, suitably attached, so that upon the operation of the crank R, the upright shaft O, is revolved, and by means of its threaded end is raised up, thereby raising the bevel wheel N, and pressing upon the bevel wheels M, and so extending the arm K, until it comes in contact with the cable, the pressure upon which acting like a brake causes the cycles to stop.

Of course any number of these platforms can be arranged contiguously, so that their respective riders, may have the added incentive of acquiring greater speed than their neighbors.

Having thus described our invention and its manner of construction, what we claim, and desire to secure by Letters Patent, is—

1. In combination with the circular platform A, and the polycycles B, the bent bar D, arranged with the threaded ends and caps, and made in such curves as to conveniently cover the cycles, in manner as described.

2. The combination of the bent rod I, the cable J, the arm K, the bevel wheels M and N, the shaft O, the geared wheels P and Q, the crank R, and the spring S, together with the circular platform A, and the cycles B, constructed and arranged substantially as shown.

EDWARD T. NOONAN.
JOSEPH V. SCHMILL.
